FLUIDIZED-SOLID PROCESS FOR FORMING
CARBON DISULFIDERobert P. Ferguson, Cranford, N. J., assignor to
Standard Oil Development Company, a corpora-
tion of Delaware

Application March 6, 1943, Serial No. 478,310

10 Claims. (Cl. 23—206)

1

The present invention relates to the production of carbon disulfide by a cheaper and more efficient method than that which has been hitherto practiced. The invention will be fully understood from the following description and the drawing.

The drawing is a semi-diagrammatic view in sectional elevation of an apparatus for producing carbon disulfide by an improved method and indicates the flow of the materials.

Carbon disulfide is made at the present time by the direct union of carbon and sulfur. The reaction is strongly endothermic and proceeds only at a high temperature. At present the procedure is to attain the heat by striking an electric arc between carbon electrodes in a furnace packed with coke through which sulfur vapor is passed. The cost of the electric current is high and the method seems unreasonably expensive for most localities.

In the present invention a method has been devised for obtaining the heat for the reaction and the temperature required by the combustion of a portion of the coke and it is consequently cheaper since this form of heating is much less expensive than electrical methods. It has further advantages in that the method is totally continuous and is subject to a close, accurate control. Other advantages will be apparent to those skilled in the art.

Referring to the drawing, numeral 1 denotes a reaction vessel, preferably in a cylindrical form, which is divided into three separate zones, an upper heating zone marked A, a middle or reaction zone, B, which is in several reaction sections as will be described later, and a lower pre-heating zone C. These zones are separated from each other by solid cross-sectional plates 2 and 3, zones A and B by the septum 2, and B and C by the septum 3. Powdered coke is fed into an elevated hopper 4 through a double bell valve 4a, into a dispersing or suspension chamber 5. Air or other gas is added at the bottom of the zone through the pipe 6 and a dense suspension of the finely divided coke in the gas is thus prepared in 5. Some gas is released through pipe 7, preferably to equipment for recovery of the finely divided carbon. This may be a separate device or the pipe 7 may be connected into the top of the zone A, as will be explained below.

The dense dispersion of coke in gas is conveniently described as being in a suspended condition and the mixture acts in many ways like a liquid and is capable of flowing through pipes, valves, chambers and conduits, and shows both static and dynamic heads. The suspended coke

from the chamber 5 passes down through feeding standpipe 8 and into a rising pipe 9, which leads directly into the zone A of the reactor. Air is supplied by a pipe 10 and it is preferably pre-heated at 11 before it passes into the pipe 9. If desired, it may pass directly into the zone A, that is before admixture with the suspended coke. The air is insufficient for the complete combustion of the entire amount of coke fed, but is sufficient to burn enough coke to raise the remainder of the suspended mixture to an elevated temperature of the order of 1400 to 1600° F.

Reaction vessel 1 may be lined with firebrick, not shown, or otherwise adapted to withstand 15 this high temperature and the mixture of air and solid gas is added at the bottom of the zone A, preferably beneath a grid or screen 11, which acts as a distributor. Thus within the zone A, the finely divided coke in a highly heated condition 20 is suspended in the combustion gas. From the top of the zone part of the gas is removed through a cyclone separator 12 which is finely constructed in the top of the zone A. Clean gas is taken by pipe 13 to a heat exchanger 14 and thence to a 25 stack which is not shown.

Vaporized sulfur is supplied through a pipe 15 and is carried through the heater 14 wherein it is highly superheated before passing by a pipe 16 into the lower portion of zone B of the reactor 1. 30 The zone B is divided, as indicated above, into a series of reaction sections by means of grids marked 17. In this case three such sections and three grids 17a, 17b and 17c are shown, but it will be understood that two or more than three 35 sections may be employed if desired. The pulverized, suspended coke is fed into the uppermost section of zone B directly from zone A by means of a pipe 18a, which passes through the grid 11 and through the septum 2. This pipe, 40 18a, discharges into the uppermost section of zone B and preferably there is some dispersing plate or baffling means to give the dispersion an upward motion into the zone. From the uppermost section the fluidized coke passes downwardly 45 to the lower sections successively by pipes 18b and 18c and then from the lowermost section into zone C of the reactor by a pipe 18d. It will thus be seen that the fluidized carbon flows down through the several sections of zone B in a 50 roughly countercurrent relation to the vaporized sulfur which passes upwardly through the several sections of zone B. The conversion to carbon disulfide occurs during the passage through the several sections of zone B and as the temperature is considerably above the boiling point of carbon

disulfide, the vapor of that compound as it is formed passes up through zone B, finally finding exit by a pipe 19 which preferably connects with a hot, dust separator 20 which returns finely divided coke dust to zone B. The carbon disulfide vapor is then condensed in a cooler 21 and is collected in a reservoir 22.

The powdered solid leaves the lower section of zone B by means of a pipe 18d and if the flow of the two materials is so controlled and if a sufficient number of sections are provided in zone B, the solids in this fluidized mixture are largely ash and free from carbon, but it will be still at a high temperature and can be used to preheat at least a portion of the air used for the process, so that it is desirable to feed the air by the pipe 23 beneath the grid 24 within the zone C. If some carbon is still contained in the ash, it can be conveniently burned within this zone and thus the carbon will be used to supply preheat. The hot gases pass out of zone C by a pipe 25 which joins pipe 18, mentioned before. The ash is removed from zone C by a pipe 26.

It will be understood that the solids throughout the entire reaction zone are in what has been termed a "fluidized" state and the streams flow downwardly from zone to zone while the vapors and gases gradually pass upward through the apparatus. Within the reaction zones the finely divided carbon and the vaporized sulfur are as thoroughly admixed as possible and in continual agitation so that the reaction proceeds rapidly and efficiently. Within each of the sections B, the agitation is sufficiently great so that each section will be held at approximately the same temperature. This effect may be further enhanced by passing a portion of hot suspended carbon directly from the pipe 9 into the several sections of B by means of separate pipes 27. The flow down the pipes marked 18 is controlled by dampers or other types of valves which are shown on the drawing.

In order to maintain the solid in a thoroughly fluidized or suspended state, it must be reduced to a fine powder, preferably not greater than 50 mesh, and it is usual to employ powders of say 100 to 200 mesh or even finer. Gas must be added to these powders in a certain minimum quantity of the order of 1 to 2 cubic feet per 100 pounds of solid in order to effect the fluidization. If less gas be present, the solid will have a tendency to pack and will not flow through the apparatus smoothly, but if a good fluidized suspension is obtained and velocities are kept within prescribed limits, there is little tendency for the solids to pack and to plug valves or lines. Quantities of gas, considerably greater than the minimum specified above, can be added to the suspensions without undesirable effects and flow of the fluidized suspensions can be effected without the use of pumps or fans acting directly on the powdered solid by conveniently adjusting the densities of the suspensions. Thus, the density in the down pipe 8, which conducts the original suspended carbon from the chamber 5, will be considerably greater than the density of the suspension in the rising pipe 9, because of the gas added to pipe 9 by 10, so that the suspension prepared in the chamber 5 will be conducted down the pipe 8 and up through the pipe 9 without the use of pumps or fans as indicated above.

The velocity of flow within the tower is an important factor and preferably should be held within the range of 1 to 5 cubic feet per second, that is to say the upward flow of gas based on the

total diameter of the reaction zone. This is sufficient to maintain the suspension and to bring about the desired agitation. If the velocity is much above this figure, the amount of fluidized carbon carried overhead is considerably increased and while that is not greatly objectionable, it requires larger dust separating capacity than is required with the velocities set forth. The temperature within the reaction zone is within the range of 1400 to 1600° F., just as is used in the present method, and it will, of course, be understood that the reaction itself proceeds in this same general manner, but more rapidly in the present case because of the finely divided condition of the coke. The heat for the reaction, as has been mentioned before, is supplied by the combustion of a portion of the carbon and is carried in by the highly heated carbon which is to take part in the reaction. The required heat amounts to about 52,000 B. t. u. per pound of carbon disulfide formed. Most of the burned carbon is in the form of carbon monoxide and the gas recovered may be employed for various purposes. For example, it may be burned to carbon dioxide to furnish heat for various preheating some of the reactants. It may be employed in gas engines for furnishing power or for other purposes, such as for the conversion with steam to produce a gas rich in hydrogen.

I claim:

- 30 1. A process for the continuous production of carbon disulfide which comprises forming a suspension of powdered carbon in a gaseous stream comprising vaporized sulfur, said carbon being of such particle size that a majority will pass a 200 mesh screen, maintaining said suspended carbon in a fluidized state in a reaction zone at a temperature between approximately 1400° F. to 1600° F. for a time sufficient to form carbon disulfide, continually adding more carbon and vaporized sulfur, continually removing the gaseous products from the reaction zone and recovering carbon disulfide, and continually removing spent ash from said zone.
- 35 2. A process for the continuous production of carbon disulfide which comprises forming a suspension of powdered carbon in a gaseous stream comprising vaporized sulfur, said carbon being of such particle size that a majority will pass a 200 mesh screen, maintaining said suspended carbon in a fluidized state in a reaction zone at a suitable reaction temperature and for a time sufficient to form carbon disulfide, continually adding more carbon and vaporized sulfur, continually removing the gaseous products from the reaction zone and recovering carbon disulfide, and continually removing spent ash from said zone.
- 40 3. An improved process for producing carbon disulfide which comprises continuously supplying powdered coke to a vertical reaction zone, passing vaporized sulfur into the bottom of the zone and maintaining the velocity of the vapors such that the solid coke particles are maintained in a fluidized condition therein, adding air to generate heat for the reaction, withdrawing vaporized carbon disulfide and separately withdrawing a stream of fluidized solids rich in ashy constituents.
- 45 4. An improved process for producing carbon disulfide which comprises continuously passing vaporized sulfur into a reaction zone, continuously passing finely divided carbon suspended in a gaseous vehicle into said zone, maintaining a reactive temperature of 1400° to 1600° F. in said reaction zone, maintaining the carbon in a fluidized state in said reaction zone, continuously withdrawing
- 50 5. An improved process for producing carbon disulfide which comprises continuously passing vaporized sulfur into a reaction zone, continuously passing finely divided carbon suspended in a gaseous vehicle into said zone, maintaining a reactive temperature of 1400° to 1600° F. in said reaction zone, maintaining the carbon in a fluidized state in said reaction zone, continuously withdrawing
- 55 6. An improved process for producing carbon disulfide which comprises continuously passing vaporized sulfur into a reaction zone, continuously passing finely divided carbon suspended in a gaseous vehicle into said zone, maintaining a reactive temperature of 1400° to 1600° F. in said reaction zone, maintaining the carbon in a fluidized state in said reaction zone, continuously withdrawing
- 60 7. An improved process for producing carbon disulfide which comprises continuously passing vaporized sulfur into a reaction zone, continuously passing finely divided carbon suspended in a gaseous vehicle into said zone, maintaining a reactive temperature of 1400° to 1600° F. in said reaction zone, maintaining the carbon in a fluidized state in said reaction zone, continuously withdrawing
- 65 8. An improved process for producing carbon disulfide which comprises continuously passing vaporized sulfur into a reaction zone, continuously passing finely divided carbon suspended in a gaseous vehicle into said zone, maintaining a reactive temperature of 1400° to 1600° F. in said reaction zone, maintaining the carbon in a fluidized state in said reaction zone, continuously withdrawing
- 70 9. An improved process for producing carbon disulfide which comprises continuously passing vaporized sulfur into a reaction zone, continuously passing finely divided carbon suspended in a gaseous vehicle into said zone, maintaining a reactive temperature of 1400° to 1600° F. in said reaction zone, maintaining the carbon in a fluidized state in said reaction zone, continuously withdrawing
- 75 10. An improved process for producing carbon disulfide which comprises continuously passing vaporized sulfur into a reaction zone, continuously passing finely divided carbon suspended in a gaseous vehicle into said zone, maintaining a reactive temperature of 1400° to 1600° F. in said reaction zone, maintaining the carbon in a fluidized state in said reaction zone, continuously withdrawing

vaporized carbon disulfide and recovering the same free from solid carbon.

5. An improved process for producing carbon disulfide which comprises passing a stream of finely divided carbon suspended in a gaseous vehicle through a series of reaction zones wherein the carbon is maintained in a fluidized condition by addition of a further gaseous constituent, passing vaporized sulfur through said zones, removing vapors of carbon disulfide, separating solid carbon therefrom, condensing the carbon disulfide and continuously withdrawing in a separate stream fluidized solid rich in ashy constituents of the carbon.

6. An improved process for producing carbon disulfide which comprises preparing a stream of powdered coke suspended in air, burning a portion of the coke to raise the remainder to an elevated temperature, then passing the heated suspended carbon so obtained downwardly through a series of reaction zones wherein the carbon is maintained in a fluidized state, passing vaporized sulfur through said zones in the opposite direction, removing carbon disulfide so formed as a vapor, separating powdered solids therefrom, condensing the vapor and collecting the carbon disulfide.

7. A process according to claim 6 in which the heat for the reaction is supplied by the incoming stream of said heated suspended carbon.

8. A process according to claim 6 in which hot streams of said heated suspended carbon are fed into the separate reaction zones to maintain them at the desired reaction temperature.

9. An improved process for producing carbon disulfide which comprises preparing a stream of finely divided coke suspended in a gaseous vehicle, passing the stream downwardly through a series of reaction zones wherein the coke is maintained in a fluidized state by addition of vapors thereto, adding air to the first of said zones to burn a por-

tion of the coke thereby heating the remainder to an elevated temperature, passing the stream through the series of reaction zones, passing vaporized sulfur countercurrently through these zones, withdrawing carbon disulfide vapor formed in the reaction, recovering and condensing the carbon disulfide, withdrawing a stream of suspended solids from the reaction zone and directing the same into a preheating zone and passing air through the preheating zone for obtaining preheat.

10. A process for the continuous production of carbon disulfide which comprises forming a mixture comprising a suspension of powdered carbon in a gaseous stream comprising vaporized sulfur, said carbon being of such particle size that a majority will pass a 200 mesh screen, maintaining said mixture in a fluidized state in a reaction zone at a temperature between approximately 1400° F. to 1600° F. for a time sufficient to form carbon disulfide, continually adding more carbon and vaporized sulfur, continually removing the gaseous products from the reaction zone and recovering carbon disulfide, and continually removing spent ash from said zone.
